CIGARETTE HOLDER

Bertha Brueck, Rochester, N. Y.

Application February 6, 1933, Serial No. 655,513

2 Claims. (Cl. 131—51)

The invention according to one aspect thereof relates to cigarette holders.

The invention according to another aspect thereof relates to a package of cigarettes with 5 which there is included as part of the package a cigarette holder adapted for employment when a cigarette thereof is being smoked.

One object of the invention is to construct a cigarette holder so that it occupies a relatively 10 small volumetric space and therefore according to certain forms of the invention the cigarette holder is constructed of or from a relatively thin, narrow, flat strip of material capable of placement within a cigarette package without materially adding to the bulk of the package.

Another object of the invention is to provide a 15 relatively thin, long and relatively straight cigarette holder having a body portion or handle narrow in width and thin whereby the handle portion can be used in a straight or extended condition or whereby at the will of the user it can be bent as into a ring form or other shape for such employment as desired.

According to one specific mode of employing 20 the invention the cigarette holder is of a shape whereby it is adapted for use within the body portion of a container for cigarettes according to an arrangement or disposition in which the cigarette holder parallels the cigarettes and is in contact with one or more of the cigarettes of the 25 package, while according to another aspect the cigarette holder can be readily employed outside or partially outside of the body of the container but within a transparent wrapper enclosing the 30 container body in such a manner that the cigarette holder is at least partially visible from the exterior of the package.

With these and other objects in view, the invention consists in the construction and novel 35 combination and arrangement of parts herein-after fully described, illustrated in the accompanying drawing and pointed out in the claims hereto appended, it being understood that various 40 changes in the form, proportion and minor details of construction, within the scope of the claims, may be resorted to without departing from the spirit or sacrificing any of the advantages of the invention.

Reference will now be made to the accompanying drawing forming a part of this specification in which:—

Figure 1 is a perspective view of one form of cigarette holder embodying the invention.

Fig. 2 is a perspective view showing a body por-

tion of the cigarette holder of Fig. 1 bent into ring-like formation.

Fig. 3 is a perspective view of a cigarette holder of ring shape formed of a blank similar to that shown in Fig. 1 but according to Fig. 3 the material of the cigarette holder is much thicker than that of the material in the holder of Figs. 1 or 2.

Fig. 4 is a perspective view of a cigarette holder similar to that shown in Fig. 1 but slightly modified as to certain details thereof.

Fig. 5 is an end view of the cigarette holder shown in Fig. 4, Fig. 5 being a view looking in the direction of the arrow 5 of Fig. 4. Also in Fig. 5 there is indicated by dotted line a portion of a cigarette being held thereby.

Fig. 6 is a perspective view showing how the cigarette holder of Fig. 1 can be bent whereby it can readily serve as a support by which the cigarette can be supported on but in spaced relationship in respect to a table top or other supporting surface.

Fig. 7 is a perspective view of a cigarette package with the cigarette holder of Fig. 1 positioned in association therewith. The package of Fig. 7 comprehends the main or body portion of 80 a container within which cigarettes are located, a transparent enclosing wrapper and a cigarette holder arranged so that it extends in substantial parallelism with the cigarettes.

Fig. 8 is an end view in which a portion of the 85 container body and wrapper therefor has been broken away and according to this view it will be noted that the cigarette holder is located exteriorly of the container body but within the transparent wrapper.

Fig. 9 is a view similar in many respects to that of Fig. 8 but it will be noted that according to Fig. 9 the cigarette holder is within the container body and is positioned so that it is engaged by one or more cigarettes therein.

Reference will now be made to the drawing in detail.

One form of cigarette holder is indicated by 1 and it comprises a fork shaped cigarette receiving and holding end portion 2 and a handle or 100 longitudinally extending body portion 3. The cigarette holder of this figure is preferably composed of or provided by thin sheet metal such as aluminum, tin, zinc, brass or any other soft pliable material capable of being readily bent into 105 various shapes and particularly for the purposes herein set forth. In fact the material which is employed for this holder can be of the precious or semi-precious type should one desire to use the more expensive material but in the main the

present holder is designed and particularly adapted for the use as a cheap construction which can be included in or with a package of cigarettes or in other words, distributed with the cigarettes at the time when the cigarettes are sold to the ultimate user. It will therefore be manifest that if one desires to use the cheaper materials that it will be feasible to improve the external appearance or finish thereof as by dipping into solutions of various kinds suitable for accomplishing ornamental plating or by otherwise finishing the article according to the desires of the particular producer.

It will be noted that in the cigarette holder of Fig. 1 the fork shaped cigarette receiving and holding section 2 thereof comprises cooperating tines 2a and 2b separated by a slot or slotted portion a. Each of these tines or prongs comprise a free outer end section 4 which directly engage the cigarette, and an intermediate section 5. The intermediate sections 5 serve as spacing members or portions for insuring a positioning of the cigarette in spaced relationship in respect to the handle or body portion 3 of the holder. The cigarette holder may be scored as at 6 to indicate a place for bending if desired. At this junction it will also be pointed out that a face portion 7 of the holder may be employed for receiving advertising or other legend should one desire to place the same thereupon. An inspection of this Figure 1 shows that the holder as a whole in its longitudinal direction is relatively straight, that it has a substantial length, to-wit, a length substantially equal that of a cigarette as is manifest from an inspection of Fig. 7, that it is relatively narrow as compared to its length and that it is of thin, flat sheet material.

In general the material is of such thickness that by relatively slight pressure by the fingers of the user the handle portion can be shaped so as to provide an open ended ring-like section 8 such as shown in Fig. 2. If desired, however, this cigarette holder can be made of much thicker material whereby tools or other appliances might be required to shape it and such a holder is indicated fully bent to provide a ring shaped section 8 as shown in Fig. 3.

In Fig. 6 there is shown a form in which the holder of Fig. 1 can be readily shaped as by the user. Fig. 4 shows a holder similar in fundamental respects to that of Fig. 1 but slightly modified so that the tines of the fork portion are bent as by angular movement in respect to a longitudinal axis of the holder as a whole so as to provide a wider cigarette engaging portion than would be the case if a thin edge of the forked portion were the only part that engaged the cigarette. Fig. 4 indicates a manner in which the construction of Fig. 1 can be employed or bent if one desires to do so. The cigarette holder of Fig. 4 is provided by a metal strip 1' slotted or cut along the line a' so as to provide the fork shaped cigarette receiving and holding portion 2' which comprises the cooperating tine members 2a' and 2b'. Each of these tines is bent in the manner indicated and so as to provide the outer free cigarette engaging section 4' and an intermediate or spacing section 5'. The handle is designated by 7' and may be scored as along the line 6'. The surface 7' of the handle or straight portion 3 of the holder may be provided with an advertising legend or any other marks which the producer may desire to place thereupon.

Fig. 5 shows in place the arrangement of the

tines of the fork section of Fig. 4 in respect to a cigarette when held thereby.

Figs. 8 and 9 show cigarettes arranged in the package of Fig. 7 and illustrate how the cigarette holders of Figs. 1 or 4 can be incorporated as part of the package. The cigarettes are designated as 8. The package includes any suitable container as of cardboard, heavy paper or other suitable material providing a main body portion or main body member as 9 within which the cigarettes are encased, and a transparent wrapper 10 of thin sheet material as "Cellophane" completely encasing the body portion of the container.

According to Fig. 8 it will be seen that the cigarette holder 1 is indicated exteriorly of the body portion of the container, that it parallels the cigarettes within the container and that the cigarette holder is positioned so that it is visible, or at least so that a portion of the cigarette holder is visible from the exterior of the package as is indicated by Fig. 7, while according to the arrangement shown in Fig. 9 the cigarette holder 1 is indicated entirely within the container body and is positioned or disposed so that it parallels the cigarettes within the container and so that it is in engagement with one or more of the cigarettes within the container.

As previously indicated it will be noted from an inspection of Fig. 7 that the cigarette holder is preferably of a length substantially equal to that of the cigarettes but that it is of such shape that it can be readily incorporated in the package or arranged in position approximate the cigarettes of the package without materially changing the size or shape of the package. It is also of such shape that a corner of the casing material providing the package can be torn or otherwise removed from place whereby access is readily had to both the cigarettes or a portion thereof and to the holder, as is manifest from an inspection of Fig. 8 or 9. It will also be observed that the cigarette receiving and holding section of the holder being of yieldable and readily bendable material can be bent, shaped or adjusted for holding the cigarette according to the desires of a particular user and that the body portion of the cigarette holder can also be accordingly bent so as to respond to the wishes of a user as to shape thereof.

It will be understood that the form of holder shown in Fig. 3 is made of heavier metal than the form shown in Fig. 2, as previously stated, and both forms (Figs. 2 and 3) are provided with the split ring formations whereby the cigarette may be mounted on the user's index or other finger to thereby enable the user to turn leaves of books or otherwise use both hands without laying aside the cigarette and the Fig. 3 structure is such as to provide for an article of manufacture formed for sale or for use and of such material as to provide for spring clamping jaws to insure a firm gripping of the cigarette by the spring action of the jaws without manipulation of the metal of the holder by the user.

The body portion of each holder is formed of a single piece of material, as shown, with one end bifurcated or recessed to provide outer gripping fingers and inner parallel members which are adapted to space the fingers from the body portion and from the ring portion if the device is formed as in Figs. 2, 3, 5 and 6 and at the opposite end of the body portion of the single piece of material there is provided a perforation 3' which may be utilized to receive a tack or other fastening device not shown in the event that it is

desired to suspend the holder from a nail in the wall or if it is desired to secure a holder such as that shown in Fig. 6 to a table or other support, as should be well understood.

5 What is claimed is:

1. A cigarette holder formed of a single piece of material forming a body portion and which is recessed at one end to provide outer spaced curved cigarette gripping members and inner spaced parallel members disposed between the outer curved members and the body portion of the single piece of material, the spaces between the gripping members and the parallel members being unobstructed, said body portion being in the form of a split ring with one end of said body portion lying adjacent the inner ends of said parallel members and spaced slightly therefrom whereby to fit the holder on a finger of the

user and whereby to space a lighted cigarette in the gripping members from the body of the holder and the user's hand.

2. A cigarette holder formed of a single piece of material forming a body portion having a perforation at one end and which is recessed at the other end to provide outer spaced curved cigarette gripping members and inner spaced relatively short parallel members which are disposed between the outer curved gripping members and the body portion of the single piece of material, said body portion being so disposed with relation to the other aforesaid elements that the said inner parallel members and said gripping members project outwardly and laterally beyond the perforated end of said body portion.
